DISPENSER FOR TOILET TANKS OR THE LIKE

George A. Sarandos, 6906 Ashcroft,
Houston, Tex. 77006

Filed June 4, 1971, Ser. No. 150,264

Term of patent 14 years

Int. Cl. D23—99

U.S. Cl. D23—3

FIG. 1 is a view in elevation of a dispenser for toilet tanks or the like showing my new design;

FIG. 2 is a top plan view of the container; and

FIG. 3 is a bottom view of the container.

I claim:

The ornamental design for a dispenser for toilet tanks or the like, as shown.
